TOTALIZER ALIGNER MEANS

Mayo A. Goodbar, Everett H. Placke, and Carl G. Falkner, Dayton, Ohio, assignors to The National Cash Register Company, Dayton, Ohio, a corporation of Maryland

Original application July 17, 1948, Serial No. 39,278, now Patent No. 2,616,623, dated November 4, 1952. Divided and this application November 14, 1951, Serial No. 256,298

6 Claims. (Cl. 235—60)

This invention relates to totalizer-aligning means for cash registers and accounting machines.

This application is a division of application Serial No. 39,278, filed July 17, 1948, now Patent No. 2,616,623, issued November 4, 1952.

The object of the invention is to provide shiftable interspersed totalizers with a novel aligning mechanism for accurately aligning a selected totalizer with the actuators therefor.

With this and incidental objects in view, the invention includes certain novel features of construction and combination of parts, a preferred form or embodiment of which will be hereinafter described with reference to the drawings which accompany and form a part of this specification.

Of said drawings,

Fig. 1 is a top view of the keyboard of the machine in which the present invention is illustrated.

Fig. 2 is a top plan view of the rear totalizer line and shows the shifting mechanism and the adjustable aligning means.

Fig. 3 is a detail view of a part of the totalizer-engaging mechanism.

Fig. 4 is a detail view of the mechanism shown in Fig. 3, shown in moved or totalizer-engaging position.

Fig. 5 is an enlarged detail view of the amount differential mechanism.

Fig. 6 is a sectional view taken just to the right of the second transaction bank and shows the second transaction bank differential mechanism and the connections for shifting the interspersed totalizer lines.

Fig. 7 is a detail view of the driving mechanism for the transaction differential shown in Fig. 6.

Fig. 8 is a detail view of the beam-setting mechanism shown in Fig. 6.

Fig. 9 is a detail view of certain parts shown in Fig. 6.

GENERAL DESCRIPTION

The machine to which the present invention is shown applied is provided with three lines of totalizers, which, as illustrated in said parent case, are designated the front, or "batch," totalizer line; the rear, or "transaction," totalizer line; and the upper, or "list," totalizer line. The "batch" and "transaction" totalizer lines comprise interspersed totalizers, each set of which is carried on a shiftable shaft, so that a desired set of totalizer wheels are aligned with differential actuators for receiving entries and for having totals read therefrom. The shafts are shifted by drum cams under control of transaction keys and a transaction differential. In order to provide for accurate alignment of the totalizer wheels with the actuators, a novel aligning mechanism is provided, which is adjustable within close tolerances to obtain the best possible alignment therebetween.

Front, or "batch," totalizer line

As disclosed in said parent case, the "batch" totalizer line comprises two interspersed totalizers consisting of totalizer elements 350 (Fig. 5). The totalizer elements 350 are rotatably mounted on a totalizer shaft 351. The shaft 351 is shiftably mounted in bearings carried by a pair of engaging arms 352, located adjacent frame plates 194 and 199 (see Fig. 2). The engaging arms 352 are mounted on a shaft 353 so as to rock thereon. Each arm 352 is provided with a cam slot 354 (Figs. 3 and

2

4). Engaging each cam slot 354 is a roller 355 carried by an arm 356 mounted on a stud 357, one carried by each side frame 194 and 199. Each arm 356 is also provided with a stud 358 projecting into an open slot in each arm 359 secured on the rock shaft 353. The rock shaft 353 is actuated during the machine operation in either adding or total-taking timing in a manner described in the parent case.

The shaft 351, together with the totalizer elements 350, is shifted endwise to properly align one or the other of the two interspersed totalizers with differentially movable actuator racks 304 (Figs. 3, 4, and 5), controlled for movement by amount keys 160 in the usual manner. The manner in which the totalizer elements 350 are shifted in respect to the actuator rack 304 is described herein-after.

Front, or "batch," totalizer aligner

When the totalizer wheels 350 are in their disengaged positions, as shown in Fig. 3, an aligner 360, engaging between the teeth of the wheels 350, maintains the totalizer wheels against rotation. The aligner 360 is long enough to span the entire totalizer line and extends from the frame 194 to the frame 199. This aligner is in the form of a yoke, having a bail and two arms 366, each of the latter having a stud 362 projecting into a cam slot 361 of the arm 359. Upon rocking of the shaft 353, the cam slots 361, engaging studs 362 on aligner arms 366, disengage the aligner 360 from the totalizer elements 350, after the totalizer elements are properly engaged with the actuator racks 304, as shown in Fig. 4.

Rear, or "transaction," totalizer line

The rear totalizer line includes eight sets of interspersed totalizer elements 370 (Figs. 2 and 5). A ninth totalizer is shown in Fig. 2 to illustrate the maximum number of totalizers which can be provided. However, the ninth totalizer is shown in the position corresponding to the "add print" key, which key, in the present disclosure, prevents the rear totalizer from becoming engaged with its actuators in the manner disclosed in said parent case. Therefore, as disclosed therein, nothing will ever be entered into the ninth totalizer. Therefore, for the purpose of this description, it is assumed that only eight totalizers on the rear totalizer line are actually used, which is adequate for the application illustrated.

The engaging mechanism for the rear totalizer line is identical with that described for the front totalizer line. The totalizer elements 370 are mounted on a shaft 371 shiftably mounted in bearings in a pair of arms 372, rotatably mounted on a rock shaft 373. The arms 372 are provided with notches similar to the notch 354 (Figs. 3 and 4), with which rollers 375 (Fig. 2) of arms 376, similar to the arm 356 (Fig. 4), engage. The arms 376 are provided with rollers 378 (Fig. 2), similar to the rollers 358, which project into open slots in rocking arms 379 pinned to the shaft 373. When the shaft 373 is rocked in the manner described in the parent case, the cam arms 379, through rollers 378, rock the arms 372 to engage the totalizer wheels 370 with the actuator racks 305.

An aligner 380, similar to the aligner 360, is provided for the rear totalizer line and is operated by the arms 379 in like manner.

During the operation of the machine, the totalizer shaft 371 is shifted laterally in bearings of arms 372, under control of the transaction keys, to align the proper set of totalizer wheels 370 with the actuators 305. Thereafter, the shaft 373 is given a rocking movement to engage the selected set of totalizer elements 370 with the actuators 305 in the proper timing, so that either adding or total-taking operations may be performed in the selected totalizer.

Totalizer aligner adjusting means

Each totalizer shaft 351 and 371 has provided thereon a novel means for adjusting the totalizer elements in respect to the actuators 304 and 305, so that accurate alignment can be obtained. This novel construction is the same for both totalizer shafts, and therefore the mechanism is illustrated in connection with the rear totalizer

line only. This mechanism is best disclosed in Figs. 2, 3, and 4.

The left-hand end of the shaft 371 (Fig. 2) is provided with threads to receive an adjustable aliner member 381. The aliner member 381 consists of a castellated nut having aliner discs 382 thereon, arranged to engage alining slots 383 in an alining block 384 mounted on the left side frame 194 when the shaft 371 is moved to engage the totalizer wheels with the actuators. The right-hand end of the shaft 371 is threaded at 385 to receive an adjusting nut 386. A yoke 387 straddles the nut 386, and the yoke is differentially shifted sidewise by a drum cam 388 under control of the transaction keys, in a manner to be described hereinafter, to selectively shift the totalizer wheels 370 in relation to the actuators 305 for selecting a totalizer. When the totalizer shaft 371, together with the totalizer wheels 370, is assembled in the machine, the shaft 371 is adjusted endwise by the turning nut 386 to properly align the selected set of totalizer wheels 370 with the actuator racks 305. Thereafter, a cotter pin 377 is inserted through notches in one face of the nut 386 and through an opening in the shaft 371. This holds the selected totalizer elements 370 in alignment in respect to the shifting drum cam 388. After the first adjustment has been made by means of the nut 386, aliner member 381 is properly adjusted to align the aliner discs 382 with the aliner slots 383.

After the aliner member 381 properly aligns the discs 382 with the slots 383 in accordance with the adjustment of the nut 386, a cotter pin 3901 is inserted through the notches in the aliner member 381 and through an opening in the shaft 371.

The novel arrangement including the two nuts 381 and 386 provides a fine adjustment for accurate alignment of the interspersed totalizer wheels 370 with respect to the actuator racks 305. The front totalizer shaft 351 is provided with a like adjusting feature whereby the two "batch" totalizers may be accurately aligned with the actuators 304.

Transaction keys

The transaction keys for controlling the various functions of the machine are arranged in two banks, as shown in Fig. 1. The keys 101 to 108 inclusive control the selection of totalizers into which amounts are to be added, in addition to controlling other operations in the printer section of the machine in the manner described in the parent case. This bank of keys will be referred to herein as the second transaction bank. The keys 110 to 118 inclusive control the time and the manner of operation of the totalizer engaging and disengaging mechanism, together with controlling certain functions of the printing mechanism described in the parent case.

Coacting with the studs 579 of the keys 101 to 109 inclusive is a differentially settable slide 689 (Figs. 6 and 9). The studs 579 on the transaction keys alternately project to the right and left into the path of alternately arranged ears 690 formed on the slide 689. The relationship between the studs 579 and the ears 690 is such that, on operation of the machine with a key depressed, the slide 689 is arrested in a position commensurate with the position of the depressed key. The slide 689 is slotted at its front and rear ends to be supported by, and slide on, collars 691 and 692 carried by studs 693 and 694, respectively. The studs 693 and 694 are riveted on the frame 182.

The slide 689 is provided with teeth 696 (Fig. 9) meshing with a segment 697 of an arm 698 having a slot 699, into which projects a stud 700 of a latch 701 (Figs. 7 and 8). The arm 698 is rotatably mounted on a stud 702 carried by the frame 182 and by the side frame (not shown). The latch 701 is pivotally mounted on a stud 703 carried by an arm 704 also pivotally supported on the stud 702. A beam 705 is pivotally mounted on the arm 704 by a stud 706. The free end of the beam 705 is provided with a stud 707, which projects into a slot 708 of an arm 709, also pivoted on the stud 702. The arm 709 is provided with a segment 710, meshing with teeth 711 (Fig. 6) of a type setting and control slide 712. The control slide 712 is slidably mounted on the aforesaid collars 691 and 692 and at its upper end by a stud 688 mounted in the framework of the machine.

The latch 701 (Figs. 7 and 8) is provided with a toe 713 normally engaging a notch 715 of a differential driver 716. The differential driver 716 is pivoted on the stud 702 and is provided with a notch 717, into which pro-

jects a stud 718 on the free end of a lever 719 pivoted on a stud 720 carried by the framework of the machine. The lever 719 is secured to an arm 733 (Fig. 8) by a hub 721. The arm 733 is provided with a pair of rollers 722, which coact with a pair of cam plates 723 secured to the driving mechanism of the machine. The lever 719 (Figs. 7 and 8) is provided with a roller 724, which is movable into engagement with a surface 725 of the beam 705 in a manner to be described presently.

When the cam plates 723 are rotated, the arm 733 is rocked clockwise (Fig. 6) to rock the lever 719 clockwise. Clockwise movement of the lever 719, through the stud 718 and the notch 717, rocks the differential driver 716 also clockwise. Clockwise movement of the driver 716 carries with it the latch 701 and, through the stud 700, rocks the arm 698 (Fig. 9) clockwise. Clockwise movement of the arm 698, by the segment 697, moves the slide 689 to the right (Fig. 6) until an ear 690 thereon comes into contact with the stud 579 of a depressed key. This arrests the slide 689 in a position commensurate with the depressed key and at the same time positions the arm 698 (Fig. 9) in a corresponding position. Arresting of the arm 698, through its cam slot 699 acting on the stud 700, cams the latch 701 counter-clockwise around its stud 703, thus withdrawing the toe 713 from the notch 715 to arrest further movement of the arm 704. Counter-clockwise movement of the latch 701 (Fig. 8) cams an ear 726 thereon into a corresponding notch 727 (Fig. 6) of a locking plate 728 supported by the studs 693 and 720. Continued movement of the driver 716, after the latch 701 has been disengaged therefrom, moves a concentric surface 729 (Fig. 7) thereof beneath the toe 713 and positively locks the latch 701 and the arm 704 in adjusted position, with the result that the stud 706 for the beam 705 is also locked in an adjusted position corresponding to the depressed key.

During the clockwise rocking movement of the lever 719, the roller 724 thereon comes into engagement with the surface 725 of the beam 705 and rocks the beam 705 around the stud 706 as a center. Movement of the beam 705 around the stud 706 cams the stud 707 on the lower end thereof into the slot 708 and rocks the arm 709 and the segment 710 into a position corresponding to the position in which the arm 704 has been adjusted and locked by the latch 701. This adjustment of the segment 710, through the teeth 711 on the slide 712, positions the slide 712 corresponding to the adjusted position of the differential slide 689.

After the control slide 712 has been positioned by the beam 705 in the manner just described, the cams 723 return the levers 719 counter-clockwise to restore the differential driver 716 into its home position. During this counter-clockwise movement of the driver 716, when the notch 715 again comes beneath the toe 713, the toe 713 drops behind the notch 715, and, upon continued clockwise movement, the driver 716, acting through a roller 714 thereon, engages the arm 704 and restores the arm 704 and the latch 701 to their home positions. During this movement, the segment 710 and the control slide 712 are held in their adjusted positions by means described hereinafter, and therefore the beam 705 pivots around the stud 707. The segment 710 remains in the adjusted position until readjusted during the next succeeding cycle of operation.

A counter-balancing plate 730 (Fig. 9) is pivotally mounted on the stud 702 adjacent the slide 689 and has a slot 731, through which the stud 700 on the latch 701 projects. A spring 732, stretched between the counter-balancing plate 730 and the arm 698, normally maintains the parts in the positions shown in Fig. 9. If, during the operation of the machine, the latch 701 has a tendency to withdraw prematurely from the notch 715 due to centrifugal force, the plate 730 prevents such movement. When the arm 698 is positively arrested, upon an ear 690 on the slide 689 coming into contact with the stud 579 of a depressed key, the stud 700, operating in the cam slot 699, rocks the latch 701 counter-clockwise in the manner described above. Counter-clockwise movement of the latch 701 moves the stud 700 thereon in the cam slot 731 to rock the counter-balancing plate 730 clockwise against the action of the spring 732. Since it is necessary to stretch the spring 732 to move the stud 700 in the cam slot 699, the spring

732 and the plate 730 act to prevent premature disengagement of the latch 701 from its driver 716.

Type wheel setting mechanism

The control slide 712 (Fig. 6) for the second transaction bank controls the setting of a symbol-printing type element 755 in each of the three groups of type elements shown in the parent case.

Formed on the under side of the control slide 712 (Fig. 6) are a series of teeth 756, meshing with a pinion 757, which is connected to a segment 758 by a sleeve 759. The segment 758 meshes with a ring gear 760 carried by a disc 761 mounted on the shaft 632. The ring gear 760 has inner teeth meshing with a pinion 762 carried by a square shaft 763. Also carried by the square shaft 763 are pinions, similar to the pinion 762, adjacent each one of the three ring gears 764, one being provided for each group of type wheels. Meshing with each ring gear 764 is an intermediate pinion 765 on the shaft 524. Meshing with each intermediate pinion 765 is a ring gear 766 meshing with the respective type wheels 755. Through the connections just described, the setting of the control slide 712 adjusts the type carrier 755 into a position corresponding to the position to which the control slide 712 is adjusted by the differential mechanism under the control of the depressed keys 101 to 108 of the second transaction bank to set a symbol at the printing line to identify the key which was depressed.

Totalizer-selecting mechanism

The two interspersed totalized lines—namely, the Rear totalizer line on the shaft 371 (Fig. 5) and the Front totalizer line on the shaft 351—are shifted to select a totalizer under control of the keys 101 to 108 in the second transaction bank through the control slide 712.

Near the upper, or right-hand, end of the control slide 712 (Fig. 6), and formed on its under side, are a series of teeth 767 in mesh with a segment 768 rotatably supported on the shaft 302. Connected with the segment 768, by a hub 769, is a gear 770 (see also Fig. 2). The gear 770 meshes with pinions 771 secured to the drum cams 388 for the Rear and Front totalizer shifting lines. The totalizer-shifting cams 388 are rotatably mounted on shafts 389. Each drum cam 368 is provided with a cam race 772, into which projects a roller 773 of the beforementioned yoke 387.

When the control slide 712 is adjusted under control of a depressed key 101 to 109, each drum cam 388 is rotated an extent commensurate with the depressed key. Each cam race 772, acting on an associated roller 773, slides the corresponding yoke 387 endwise on a pair of shafts 774 and 775 an extent sufficient to select the proper totalizers on the interspersed totalizer lines, as described hereinbefore, alining the proper sets of totalizer wheels 350 and 370 with the actuator racks 304 and 305, respectively.

After the control slide 712 (Fig. 6) has been properly adjusted under control of the depressed key 101 to 109, an aliner 778, mounted on a shaft 776, is rocked to engage an alining segment 777, also secured to the hub 769, to maintain the drum cam 388 in its proper adjusted position during the time the totalizers are engaged with the actuator racks 304 and 305.

To actuate the aliner 778, a pair of cams (not shown) are provided, which cams, together with their driving connections, including a link 784, are shown and described in the above-mentioned parent case.

While the form of mechanism shown and described herein is admirably adapted to fulfill the object primarily stated, it is to be understood that it is not intended to confine the invention to the one form or embodiment disclosed herein, for it is susceptible of embodiment in various other forms.

What is claimed is:

1. In a machine of the class described, having a plurality of interspersed totalizers; actuators therefor; a supporting member for the totalizers; and cam means to selectively shift the totalizers in relation to the actuators; the combination of connections between the supporting member and said means, said connections including a castellated nut, threads on said supporting means on which the castellated nut is turned, means coacting with the castellated nut whereby the supporting means is adjusted to aline the totalizer with respect to

the actuators by turning the castellated nut, and a locking means coacting with the castellated nut and the supporting means to lock the castellated nut in adjusted position.

- 5 2. In a machine of the class described, having a plurality of interspersed totalizers; actuators therefor; a supporting means for the totalizers; and cam means to selectively shift the totalizers in relation to the actuators; the combination of connections between the supporting member and said means, said connections including a nut, threads on said supporting means on which the nut is turned, a yoke straddling the said nut, and a roller on said yoke engaging the cam means whereby the yoke is held in fixed relation with the cam means, said nut when turned on said threads acting to adjust the supporting means relatively to the actuators to precisely aline the totalizers with the actuators in relation to the cam means.
- 10 3. In a machine of the class described, having a plurality of interspersed totalizers; actuators therefor; a supporting means for the totalizers; and cam means to selectively shift the totalizers in relation to the actuators; the combination of connections between the supporting member and said means, said connections including a member adjustable on said supporting member, a member coacting with said cam means and said adjustable member to precisely aline the totalizer with the actuators relative to the cam means, a fixed aliner member on the framework of the machine, and an adjustable aliner engageable with the fixed aliner and carried by said supporting means, when a selected totalizer is engaged with the actuators, said adjustable aliner consisting of a means having alining members movable in respect to the fixed aliner to precisely aline the alining members with the fixed aliner after said adjustable means has been adjusted in respect to the totalizer, the actuators, and the cam means.
- 15 4. In a machine of the class described, having a plurality of interspersed totalizers; actuators therefor; a supporting means for the totalizers; and cam means to selectively shift the totalizers in relation to the actuators; the combination of connections between the supporting member and said means, said connections including a nut, threads on said supporting means on which the nut is turned, means coacting with the nut whereby the supporting means can be adjusted to aline the totalizer in respect to the actuators by turning the nut on the threads, a stationary aliner on the framework of the machine, a second nut having alining members thereon to engage the stationary aliner when a selected totalizer is engaged with the actuators, a second set of threads on the supporting means on which the second nut is turned to be moved relatively to the stationary aliner to precisely aline the alining members with the stationary aliner after such supporting means has been adjusted in respect to the totalizers, the actuators, and the cam means.
- 20 5. In a machine of the class described, having a plurality of interspersed totalizers; actuators therefor; a supporting member for the totalizers; and cam means to selectively shift the totalizers in relation to the actuators; the combination of connections between the supporting member and said means, said connections including a castellated nut, threads on said supporting means on which the castellated nut is turned, means coacting with the castellated nut whereby the supporting member is adjusted to aline the totalizer with respect to the actuators by turning the castellated nut, a locking means coacting with the castellated nut in the supporting means to lock the castellated nut in adjusted position, a stationary aliner on the framework of the machine, a second castellated nut having alining members thereon to engage the stationary aliner when the selected totalizer is engaged with the actuators, a second set of threads on the supporting means on which the second castellated nut is turned to be moved relatively to the stationary aliner to precisely aline the alining members with the stationary aliner after said supporting means has been adjusted in respect to the totalizer, the actuators, and the cam means, and means to lock the second castellated nut in adjusted position.
- 25 6. In a machine of the class described, having a plurality of interspersed totalizers; actuators therefor; a supporting member for the totalizers; and cam means to selectively shift the totalizers in relation to the actuators;

5
ators; the combination of connections between the supporting member and said means, said connections including a nut, threads on said supporting means on which the nut is turned, a yoke straddling said nut, a roller on said yoke engaging the cam means, whereby the yoke is held fixed in relation to the cam means, said nut when turned on said threads acting to adjust the supporting means relatively to the actuators to precisely align the totalizers with the actuators in relation to the cam means, a fixed aliner carried by the framework of the machine, a second nut, a second set of the threads on the supporting means on which the second nut turns, and alining members on the second nut engageable with the fixed aliner when the selected totalizer is engaged

with the actuators, said second nut turnable on the second set of threads to precisely adjust the alining members with the fixed aliner after the totalizer has been precisely adjusted with respect to the actuators and the cam means.
